UNITED STATES PATENT OFFICE.

WILLIAM J. KLEIN, OF BUFFALO, NEW YORK.

COMBINED BELL AND BUZZER.

1,293,120.

Specification of Letters Patent.

Patented Feb. 4, 1919.

Application filed May 1, 1917. Serial No. 165,714.

To all whom it may concern:

Be it known that I, WILLIAM J. KLEIN, a citizen of the United States, residing at Buffalo, in the county of Erie and State of New York, have invented certain new and useful Improvements in Combined Bells and Buzzers, of which the following is a specification.

This invention relates to an improved combined bell and buzzer and has as its 10 primary object to provide a device of this character designed to eliminate the use of separate devices for the above purposes and wherein the mechanism of the bell and the buzzer will be mounted upon a common base 15 to be inclosed within a suitable cap therefor.

The invention has as a further object to simplify the construction of the bell as well as to simplify the construction of the buzzer so that the combined device may be placed 20 upon the market at a minimum cost.

The invention has as a further object to so mount the mechanism of the bell and buzzer that the electrical connection with the said mechanism will include the metallic 25 base of the device as a common return.

And the invention has as a still further object to provide a construction wherein the wires electrically connecting the bell and buzzer, as well as the binding posts employed, will all be concealed within the dust cap of the device so that the device will thus 30 present a neat and attractive appearance.

Other and incidental objects will appear as the description proceeds and in the drawings wherein I have illustrated the preferred embodiment of the invention and wherein similar reference characters designate corresponding parts throughout the several 35 views.

40 Figure 1 is a perspective view of my improved bell and buzzer with the cap of the device removed.

Fig. 2 is a side elevation of the device,

45 Fig. 3 is a detail perspective view particularly illustrating the base of the bell and buzzer as well as the construction of the contact posts carried thereby,

Fig. 4 is a plan view of the device particularly showing the arrangement of the electro-magnets employed as well as the mounting of the armatures co-operating therewith,

50 Fig. 5 is a rear plan view illustrating the manner in which the contact posts are engaged with the insulating plate connected to the body of the device, and

Fig. 6 is a fragmentary sectional view taken on the line 6—6 of Fig. 4 and particularly showing the mounting of the electro-magnets.

In carrying out the invention, my improved device is formed with a base or body 10 provided with a marginal flange 11 and having a reduced extension or neck 12 extending from one extremity thereof. The 15 base may be cast or formed of molded insulation, but is preferably constructed from sheet metal. Connected with the extension 12 is the bell 13. Struck from the lower extremity of the base 10 at one side thereof 20 is an upstanding post 14, while a similar post 15 is struck from the opposite side of the base adjacent its upper extremity. Formed in the base at a point opposite the post 15 is an opening 16 while a similar 25 opening 17 is formed in the base at a point substantially opposite the post 14. The base is further provided with an elongated opening 18 immediately at the inner extremity 30 of the post 14 with the opening 18 extending 35 toward the opening 17.

Seating against the rear side of the base and housed within the flange 11 thereof is a plate 19 of suitable insulating material. This plate is connected at its upper extremity with the base by a screw or other suitable fastening device 20 while the lower extremity of the said plate is secured to the base by a lug 21 extending from the base at the lower edge of the post 14. Connected 40 with the base at one side of the opening 18 is a binding screw 22, and mounted upon the plate 19 to project within the said opening are spaced binding posts 23 and 24 respectively, equipped at their outer extremities with binding screws similar to the screw 22 and arranged in alinement therewith. The binding posts 23 and 24 are seated flat against the plate 19 to overhang the lower edge thereof and formed on the inner extremities 45 of the said posts are lateral lugs 27 extending through the plate for connecting the posts thereto, the said posts being insulated with respect to the base by the said plate. Mounted upon the plate to project through 50 the opening 16 of the base is a contact post 25 while a similar contact post 26 is mounted upon the plate to project through the opening 17 in the base, the plate serving to also insulate these posts with respect to the base. 55 The posts 25 and 26 are bent laterally at their inner extremities to seat against the

plate and are provided with lateral lugs 28 extending through the plate for connecting the said posts thereto. The lugs of the posts 25 and 26 as well as the lugs of the binding posts 23 and 24 are, as particularly shown in Fig. 5 of the drawings, bent over against the outer side of the plate 19 for thus securely holding the posts in position. This provides a very simple and convenient arrangement for connecting the posts with the plate but if preferred the said posts may, of course, be secured to the plate by screws or other suitable fastening devices, in the usual manner.

15 Mounted upon the posts 14 and 15 are electromagnets 29 and 30 respectively. The cores of these magnets are provided at their inner ends with squared elongated shanks 31 extending, as particularly shown in Fig. 6, through suitable openings in the said posts for holding the magnets against rotation upon the posts, the said shanks being overturned and thus connecting the magnets with the posts. It will be observed upon 20 reference to Fig. 4 that the magnets are slightly offset with respect to each other and interposed between the post 14 and the magnet 30 is a resilient armature supporting member or strip 32 engaged with the squared 25 shank of the magnet core. As illustrated in the drawings a suitable washer is preferably arranged between the strip and the body of the magnet for firmly seating the strip. The strip 32 is preferably formed 30 of resilient sheet metal and is bowed to extend toward the post 25 with the free end of the said strip reduced to provide a vibrator 33 provided with a suitable contact point to 35 cooperate with a similar contact point upon 40 the upper end of the said post. Connected with the said strip at the inner end of the vibrator is an armature 34 arranged to 45 cooperate with the magnet 29 and provided at its free end with a suitable tapper 35 arranged to act upon the bell 13.

Interposed between the post 15 and the magnet 29 is an armature supporting member or strip 36 engaged with the squared shank of the core of the said magnet and as 50 in the instance of the strip 32, a suitable washer, is, as clearly seen in Figs. 1 and 4 of the drawings preferably arranged between the strip 36 and the body of the magnet for firmly seating the strip. The strip 55 36 is identical with the strip 32 and is bowed to extend toward the post 26, being reduced at its free extremity to form a vibrator 37 provided at its outer end with a suitable contact point to cooperate with a 60 similar contact point upon the upper end of the said post. Connected to the strip 36 at the inner end of the vibrator is an armature 38 arranged to cooperate with the magnet 30 to provide a buzzer.

65 Extending beneath the plate 19 from one

of the lugs 27 of the binding post 23 is a wire 39 which is carried through the said plate and, as particularly shown in Fig. 4, is connected to one terminal of the winding of the magnet 29. Extending from the 70 other terminal of the winding of the said magnet is a wire 40 which is carried through the opening 16 in the base 10 and is connected, as illustrated in Fig. 5, to one of the lugs 28 of the contact post 25. Extending 75 beneath the plate 19 from one of the lugs 27 of the binding post 24 is a wire 41 which is carried through the said plate and through the opening 18 in the base 10 and is connected, as illustrated in Fig. 4, to one terminal 80 of the winding of the magnet 30. Leading from the other terminal of the winding of the said magnet is a wire 42 which is carried through the opening 17 in the base 10 and through the plate 19 and, as illustrated 85 in Fig. 5, is connected to one of the lugs of the contact post 26.

As will now be observed, the magnets 29 and 30 and associated parts are mounted to be inclosed within a suitable cap therefor 90 detachably connected with the base 10 in the usual manner. Since a cap of any approved type may be used for this purpose, the said cap has not been shown. However, in this connection attention is directed to the fact 95 that the binding posts 23 and 24 as well as the binding screw 22 are also arranged to be inclosed by the said cap since the circuit wires may be brought from beneath the base 10 through the opening 18 therein and connected to the said binding posts and screw. All the electrical connections of the device being thus inclosed, the device will present a neat and attractive appearance in practical 100 use.

105 From the preceding description, it will now be understood that current supplied to the post 23 will flow through the wire 39 to the winding of the magnet 29 and thence through the wire 40 to the post 25. From 110 this post, the current will then continue through the vibrator 33 of the armature 34 and through the strip 32 to the post 14. From this post, the current will then flow through the base 10 to return through the 115 binding screw 22 connected with the base. The magnet 29 will thus be energized to attract the armature 34 for actuating the tapper 35 to ring the bell 13. Current supplied to the binding post 24 will flow 120 through the wire 41 to the winding of the magnet 30. The current will then continue through the said magnet winding and the wire 42 to the contact post 26. From this post, the current will then continue through 125 the vibrator 37 of the armature 38 and through the strip 36 to the post 15. From this post, the current will then flow through the base 10 to return to the binding screw 22. The magnet 30 will accordingly be en- 130

ergized to attract the armature 38 for actuating the buzzer.

- It will therefore be seen that I provide an arrangement wherein the mechanism of both 5 the bell and buzzer is mounted upon a common base to be housed within the cap therefor and a construction adapted to displace the use of separate devices for accomplishing the purposes of the present invention.
- 10 Furthermore, I provide an arrangement wherein the single contact screw 22 provides a common return for the circuits of the bell and buzzer so that the wiring of the said circuits is accordingly simplified.
- 15 Having thus described the invention, what is claimed as new is:
1. A device of the character described including a base, an insulating plate carried thereby, spaced posts upstanding from the base, an electro-magnet mounted upon one of said posts, an armature supported by the other of said posts and arranged to co-operate with the magnet, a vibrator associated with the said armature and electrically connected with the said last mentioned post, a contact post mounted upon the said plate and projecting through the base to co-operate with the said vibrator, the plate insulating the said contact post with respect 25 to the base, a binding post mounted upon the said plate and insulated thereby with respect to the base, a second binding post mounted upon the base, electrical connection between the said first mentioned binding post and the magnet, and electrical connection between the magnet and said contact post, the post supporting the armature, the base and said last mentioned binding post providing a return for the circuit from 30 the said vibrator.

2. A device of the character described including a base, an insulating plate carried thereby, spaced posts upstanding from the base, an electro-magnet mounted upon one 45 of said posts, an armature supported upon the other of said posts to co-operate with the magnet, a binding post mounted upon the said plate and insulated thereby with respect to the base, lugs formed on the bind-

ing post and projecting through the plate 50 for connecting the said binding post thereto, a second binding post mounted upon the base, and electrical connection between said first mentioned binding post and the magnet, the base and second mentioned binding 55 post providing a return for the circuit from the magnet.

3. A device of the character described including a base provided with an opening, an electromagnet mounted upon the base, 60 an armature arranged to coöperate with the said magnet, an insulating plate carried by the base to extend across said opening, and a binding post mounted upon the plate to project at its outer end over one edge thereof 65 into the said opening for receiving a circuit wire entering through the opening from beneath the base, the said binding post being insulated by the plate with respect to the base and in circuit with the magnet. 70

4. A device of the character described including a base, an insulating plate carried thereby, an electromagnet mounted upon the base, an armature mounted to coöperate with the said magnet, a vibrator for the armature, a contact post mounted upon the said plate to coöperate with the vibrator and insulated from the base by the plate, and lugs projecting laterally from the inner extremity of the contact post and extending 80 through the said plate for connecting the post thereto. 75

5. A device of the character described including a base, a post upstanding therefrom, a contact post carried by the base and 85 insulated with respect thereto, an electromagnet carried by the base, a resilient armature supporting strip connected to the said first mentioned post and bowed longitudinally to define a bight supporting the free 90 end of the strip to extend toward the contact post, an armature carried by the free extremity of said strip to coöperate with the magnet, and a vibrator associated with the armature to coöperate with the contact post. 95

In testimony whereof I affix my signature.

WILLIAM J. KLEIN. [L. S.]
